ALEXANDER FOSTER HUMPHREY, OF PITTSBURGH, AND HOWARD F. BEAM, OF HARMONY, PENNSYLVANIA, ASSIGNEES OF ONE-THIRD TO SAMUEL A. BEAM, OF HARMONY, PENNSYLVANIA.

SWAB-VALVE MECHANISM.

1,177,035.

Specification of Letters Patent. Patented Mar. 28, 1916.

Application filed October 26, 1914. Serial No. 868,628.

To all whom it may concern:

Be it known that we, ALEXANDER FOSTER HUMPHREY and HOWARD F. BEAM, citizens of the United States of America, residing respectively, at Pittsburgh and Harmony, in the counties of Allegheny and Butler and State of Pennsylvania, have invented certain new and useful Improvements in Swab-Valve Mechanism, of which the following is 10 a specification, reference being had therein to the accompanying drawing.

This invention relates to valve mechanism, designated primarily for the employment in swabbing devices for oil wells, although it 15 can be employed for any purposes wherein it is found applicable, and has for its object to provide a mechanism of such class, in a manner as hereinafter set forth, with means to relieve the pressure fluid upon the valve 20 element of the device when the pressure exceeds a predetermined point.

Further objects of the invention are to provide a valve mechanism for the purpose set forth, which is simple in its construction 25 and arrangement, strong, durable, adjustable, efficient and convenient in its use, readily set up and comparatively inexpensive to manufacture.

With the foregoing and other objects in 30 view the invention consists of a novel construction, combination and arrangement of parts as hereinafter more specifically described and illustrated in the accompanying drawings wherein is shown an embodiment 35 of the invention, but it is to be understood that changes, variations and modifications can be resorted to which come within the scope of the claims hereunto appended.

In the drawings wherein like reference 40 characters denote corresponding parts throughout the several views:—Figure 1 is a vertical sectional view of a valve mechanism in accordance with this invention, the valve element of the mechanism being seated. 45 Fig. 2 is a top plate of a valve cage. Fig. 3 is a plan view of the adjusting element for the resilient support of the valve piston. Fig. 4 is a top plan view, broken away, of a valve piston. Fig. 5 is an elevation of a 50 modified form of valvular element.

Referring to the drawings in detail 1 denotes a casing, having its inner face at the lower end thereof provided with threads 2, its upper end contracted as at 3 and ter-

minating in a peripherally threaded neck 4 55 which is adapted to be secured to a swabbing device or any other device for which the valve mechanism is used.

The reference character 5 denotes a body portion of the valve mechanism, which is cylindrical in contour and open at each end. The lower part of the body portion 5 is of greater thickness than the upper part, as indicated at 6 and said thickened portion is formed with an outwardly projecting annular flange 7 and further provided with peripheral threads 8. The body portion 5 in proximity to the thickened part 6 is formed with a series of spaced openings 9. The body portion 5 extends in a casing 1 and the peripheral threads 8 thereof engage with the interior threads 2 of the casing 1 whereby the latter is connected to the body portion 5. 65 70 75

Vertically movable within the body portion 5 is a hollow valve piston 10, which is cylindrical in contour and has its lower end provided with an inwardly extending flange 11 and its upper end with a head 12, having a centrally disposed opening 13, having its wall beveled as at 14, to provide a valve seat 80 for a valvular element 15, the latter being globular in contour.

Arranged within the body portion 5 and abutting against the flange 11, is an expandible and contractible coil spring 16, which 85 constitutes a resilient support for the valve piston 10 and which further maintains the valve piston 10 at the upper end of the body portion 5. To arrest upward movement of the valve piston 10, a flange cap 17 is connected to said upper end of the body portion 5 and said cap 17 has a centrally disposed opening 18. Arranged in the body portion 5 at the lower end thereof, as well as having threaded engagement therewith, is an adjusting member 19, for increasing or decreasing the tension of the spring 16. 90 95

The valve piston 10 is provided with a series of spaced openings 20, which when said piston is shifted downward, are adapted to 100 register with the openings 9.

The adjusting member 19 is hollow and forms an inlet 21, to the valve body 5. The opening 13 in the head 12 constitutes an outlet for the valve body 5.

Carried by the head 12 of the valve piston 10, is a cage for the valvular element 15, and said cage consists of a plurality of vertically 105

disposed rods 22, fixedly secured to the head 12, and having attached thereto a top plate 23, formed with an opening 24.

Under ordinary working conditions fluid 5 will pass up through the adjusting member 19, valve piston 10, opening 13, and out through the neck 4 of the casing 1, but if the pressure above the valve element 13, would exceed the tension to which the spring 10 16 is set, the valve piston 10 would be lowered, so that the opening 20 will register with the opening 9, and the fluid would pass through said registering openings, through the valve body and down through the member 19.

In Fig. 5 of the drawings a modified form of valvular element is illustrated, which consists of a conical valve head 25, having a stem 26, which projects through the top plate 20 23 of the valve cage, and interposed between the top plate 23, and the valve head 25 and surrounding the stem 26 is a coil spring 27. The spring 27 normally maintains the valve head 25 in engagement with its seat.

25 The weight of the globular element 15 is such as to normally maintain it against its seat.

It may not be desirable to employ the casing 1 and under such conditions the valve body 5 can be connected, by its peripheral threads 8, with the swabbing device or any other device with which the valve mechanism is employed.

To prevent the valve piston 10 from revolving upon a vertical axis, said piston is formed with a lug 29, which extends in a vertical groove 30 formed in the inner face of the thin part of the body portion 5 and by the employment of the lug 29 in the 35 groove the openings 20 will be caused to register with the openings 9 when the valve piston 10 is shifted downward.

What we claim is:—

1. A device of the class described comprising a hollow body portion formed with openings, a hollow spring controlled valve piston having openings capable of registering with the openings in said body portion, said valve piston further provided with an 45 opening at one end and having the wall thereof constituting a valve seat, a valvular element normally engaging said seat to close the opening, and a cage for said valvular element supported by said valve piston, that 50 part of said body portion having the openings of less thickness than the remaining portion.

2. A device of the class described comprising a hollow body portion formed with 55 openings, a hollow spring controlled valve

piston having openings capable of registering with the openings in said body portion, said valve piston further provided with an opening at one end and having the wall thereof constituting a valve seat, a valvular element 65 normally engaging said seat to close the opening, and a cage for said valvular element supported by said valve piston, and a resilient support for said valve piston, said support arranged within said body portion, 70 and means connected with the body portion for adjusting the tension of said support, that part of said body portion provided with the opening of less thickness than the remaining portion. 75

3. A device of the class described comprising a hollow body portion formed with openings, a hollow spring controlled valve piston having openings capable of registering with the openings in said body portion, 80 said valve piston further provided with an opening at one end and having the wall thereof constituting a valve seat, a valvular element normally engaging said seat to close the opening, and a cage for said valvular 85 element supported by said valve piston, that part of said body portion having the openings of less thickness than the remaining portion, and a casing having said body portion extending therein and further connected to the thickened part of said body portion. 90

4. A device of the class described comprising a hollow body portion formed with openings, a hollow spring controlled valve piston 95 having openings capable of registering with the openings in said body portion, said valve piston further provided with an opening at one end and having the wall thereof constituting a valve seat, a valvular element 100 normally engaging said seat to close the opening, and a cage for said valvular element supported by said valve piston, and a resilient support for said valve piston, said support arranged within said body portion, 105 and means connected with the body portion for adjusting the tension of said support, that part of said body portion provided with the opening of less thickness than the remaining portion, and a casing having said 110 body portion extending therein and further connected to the thickened part of said body portion.

In testimony whereof we affix our signatures in the presence of two witnesses.
